CONTAINER TREATING MACHINE

Horace J. Paynter, Union, N. J., assignor to American Can Company, New York, N. Y., a corporation of New Jersey

Application March 12, 1945, Serial No. 582,313

12 Claims. (Cl. 91—49)

1
The present invention relates to a container or container part treating machine and has particular reference to devices for applying glue or other liquid materials to marginal edge portions of containers or container parts as an incident to the manufacture of the containers.

In the manufacture of certain kinds of containers or container parts it is sometimes desirable to apply a liquid coating material to the edge portions of the container or parts. In fibre containers, the coating material may be glue for adhesively securing fibre covers in place onto the ends of the containers. In metal containers, a compound lining material, lacquer, paint or other liquid may be applied for decorative purposes or for sealing end closures to container bodies. Many other such examples, including can bodies and end members may be mentioned. In all such cases, it has been found difficult under high speed operating conditions to insure and control the application of the liquid material onto the extreme edges of the container parts, especially when these parts are made from thin sheet metal or fibre stock.

The instant invention contemplates overcoming this difficulty by providing devices which operate to apply a liquid coating material to the edge portions of a container part as well as to the adjacent marginal portions so that the entire end portion of the part will be covered with a film of a desired thickness.

An object of the invention is the provision of a liquid applying device wherein controlled quantities of liquid coating material may be applied to marginal edge portions of containers or container parts.

Another object is the provision of such a liquid applying device wherein a film of liquid coating material may be applied simultaneously to a plurality of surfaces of marginal edge portions of containers or container parts so that the entire end portion of a container or a container part may be fully covered with a film of the material.

Numerous other objects and advantages of the invention will be apparent as it is better understood from the following description, which, taken in connection with the accompanying drawings, discloses a preferred embodiment thereof.

Referring to the drawings:

Figure 1 is a part elevational and part sectional view of a device embodying the instant invention, the view showing the upper end of a fibre container in section and in position in the device, parts of the device and the container being broken away;

2
Figs. 2 and 3 are plan sectional views taken substantially along the lines 2—2, 3—3 in Fig. 1, with parts broken away; and

5 Fig. 4 is a fragmentary sectional view taken substantially along the line 4—4 in Fig. 3.

As a preferred embodiment of the instant invention, the drawings illustrate a rotary device for applying liquid glue to the entire edge portion, including the inner and outer surfaces and the edge surface, of a cylindrical tubular fibre container body A preparatory to adhesively securing in place a cover which subsequently may be positioned thereon. However, the invention is equally well adapted to the use of other liquid materials such as lacquer, or paint, or compound lining materials or other substances used in the can making industry and for metal or other material container parts from which containers may be produced.

20 The application of the glue to the marginal edge portion of a container body is effected by a pair of coating rotatable members which include an applying disc or element 11 (Figs. 1 and 2) and a surrounding pressure and applying ring 12. The ring is floatingly mounted in an eccentric position relative to the applying disc so that at one place in the device as indicated by the line x—x in Fig. 2, the outer periphery of the disc is closely adjacent the inner circumference of the ring, the marginal edge of a container body A being positioned between the disc and the ring so that at this place the body is engaged by both of these members simultaneously.

35 The marginal edge portion of the container body is inserted between the disc and the ring by pushing the body toward these rotatable members. In the instant case the body is lifted straight up, preferably by a vertically operable lifter pad or the like, and is retained in this elevated position for the glue applying operation. The lifter pad may be rotatable to permit easy rotation of the body thereon.

40 Hence when the disc 11 and the ring 12 are rotated in unison, the container body is frictionally rotated therebetween and any adhesive which is carried by the disc or the ring or by both is progressively transferred, during this rotation, to the marginal edge portion or part thereof of the container body in a uniform film. When the container body has made one complete revolution, the marginal edge portion entirely around the container is fully coated. In order to provide for the coating of different diameters of containers in this manner, the applying disc and the ring are disposed at an angle to the vertical so

that only those portions of the disc and the ring that are to engage the body will be in the region of the body during the applying operation (in Fig. 1).

The applying disc or element 11 is mounted on the lower end of a rotatable shaft 14 which is journaled in an angularly disposed bearing 15 formed on a frame 16 which may be the main frame of the machine. The shaft may be rotated continuously or intermittently as desired in any suitable manner. A driving gear 17 is mounted on the shaft 14 adjacent and in spaced relation to the disc 11 for driving the pressure ring 12 as will be hereinafter explained.

The outer periphery of the applying disc 11 is formed with two adjacent angularly disposed glue applying faces, an edge face 18 and a marginal face 19. These faces are disposed at right angles to each other and join to provide a continuous corner or right angled groove extending entirely around the outer periphery of the disc. Radial recesses 20 preferably are formed in the face 19 to better hold the glue to be carried on this surface. The angular position of these applying faces relative to the angularly disposed axis of the disc is such as to insure that the faces register with and fully contact the edge portion and the inner marginal surface of the positioned container body, simultaneously as the disc rotates, best shown in Fig. 1.

The glue or other coating substance to be transferred to the edge and inner marginal surfaces of the container body during the rotation of the disc 11 first may be applied to the faces 18, 19 of the disc in any suitable manner and in the desired quantity. For example the drawings show such an application of glue to the disc by way of a supply pipe 21 which leads from a suitable source of supply of the coating material. The discharge end of the pipe is disposed adjacent the applying surfaces 18, 19 of the disc at a place where the space between the disc and the eccentrically disposed ring 12 is greatest. This is best shown in Fig. 2. A valve 22 connected into the pipe may be used to regulate the flow of the coating material from the discharge end of the pipe.

The pressure and applying ring 12 is part of a floating rotatable head 25 which surrounds the applying disc 11 and which is eccentrically disposed thereto. The head includes an outer annular support plate 26 which rests on the upper surface of the ring driving gear 17 on the drive shaft 14. The outer face or top of the plate 26 is formed with a large clearance hub 27 which terminates in an upper flange 28 and which loosely surrounds the disc drive shaft 14. The bottom of the plate is formed with a depending peripheral skirt 29 which encloses an internal ring gear 31.

The ring gear 31 is disposed in the plane of the driving gear 17 and meshes with the gear 17 at the place where the applying disc 11 and the pressure ring 12 are closest together. It is through this gear connection that the disc 11 and the pressure ring 12 are rotated in unison and at the same peripheral speed.

The ring gear 31 is maintained in the plane of the driving gear 17 and against displacement therefrom by an inner annular support plate 33 which fits in the space between the bottom of the driving gear 17 and the top of the applying disc 11 (see Fig. 1). Thus the head is locked against displacement. The inner support plate 33 is disposed in a recess 34 formed in the pressure ring

12. Ring 12 clamps tightly against the bottom of the inner plate 33.

The four principal members of the head 25, namely, the outer support plate 26, the ring gear 31, the inner support plate 33, and the pressure ring 12 are all held together as a unitary structure by a plurality of screws 36 which are located at spaced intervals around the head. These screws extend through holes formed in the three upper members of the head and are threadedly secured in the bottom pressure ring 12.

The inner edge of the pressure ring 12 is formed with a beveled glue applying face 37 which extends entirely around the inner surface of the ring. This applying face is disposed at such an angle to the axis of the ring that it is parallel with and fully contacts the outer marginal surface of the container body to be coated, as best shown in Fig. 1.

Where glue is to be transferred to the outer marginal surface of the container body it is delivered to the applying face 37 of the ring 12 in any suitable manner. By way of example, the drawings illustrate the glue being brought in by a pipe 38 which leads from any suitable source of supply of the coating material. The discharge end of the pipe is bent into close association with the applying face 37 at the place where the ring 12 and the disc 11 are spaced furthest apart (Fig. 2). A valve 39 connected into the pipe is provided to control the flow of glue from the pipe onto the applying face 37.

The normal space between the glue applying face 19 of the disc 11 and the applying face 37 of the ring 12 where they are closest together and where they engage against a container body A to be coated, is slightly less than the thickness of the container body so that pressure can be brought against the body by these faces to properly apply the glue to the body. This pressure is brought about through the pressure ring 12. For this purpose the pressure ring is yieldably mounted and is maintained under spring pressure.

The spring pressure on the pressure ring 12 is maintained by a compression spring 43 (Fig. 1) which is housed in the upper end of a pressure finger 44 disposed adjacent the drive shaft bearing 15. The inner end of the spring presses against the bearing and thus forces the upper end of the finger outwardly. The finger 44 extends down along the bearing and intermediate its length it is mounted on a pivot pin 45 carried in a pair of lugs 46 that project out from the bearing.

The lower end of the pressure finger 44 engages against the outer edge of a pressure shoe 47 (Figs. 1 and 3) that rests on top of the outer annular support plate 26 of the head 25, and occupies the space between the plate and the flange 28 on the hub 27. The inner edge of the shoe is curved and extends substantially half way around the hub.

The side edges of the shoe are formed with laterally projecting tongues 48 (Fig. 4). These tongues are slidably disposed in slideways 49 in a pair of oppositely located arms 51 which extend down from the sides of the bearing 15. The slideways are disposed parallel with the outer support plate 26 of the head 25 and are also parallel with the line x-x in Fig. 2.

With this construction of yieldable and floating mounting for the head 25, any lateral movement of the head, including the pressure ring 12 is limited to a path of travel along the line x-x in Fig. 2. It should be understood that this travel is

only slight and amounts to a mere few thousandths of an inch. In no case is the travel sufficient to unmesh the driving gear 11 from the ring gear 31. This sliding connection with the bearing 15 also serves to support the head 25 and the disc 11 housed within the head.

Hence when the marginal edge of the container body A to be coated, is introduced into the space between the disc 11 and the ring 12, as by elevating or pushing the body upwardly by means of a vertically movable lifter pad or the like (not shown) as hereinbefore mentioned. The body forces the ring outwardly to a slight extent against the resistance of the spring 43. This action causes the pressure ring 12 to press inwardly against the applying faces 18, 19 of the disc 11 to receive the adhesive from these faces onto the edge surface and the inner marginal surface of the body. Simultaneously with this pressing action the glue on the applying surface 31 of the pressure ring is applied to the outer marginal surface of the body. In this manner the entire marginal edge portion of a container body may be rapidly coated with adhesive or other substances as the disc 11 and the ring 12 rotate as hereinbefore mentioned.

The body is thereafter removed by lowering it from its position in the head, and is discharged to any suitable place of deposit. The frictional engagement of the end of the body between the disc 11 and ring 12 is not sufficient to hold the body between these elements when the lifter pad descends.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a device for applying liquid coating material to marginal edge portions of containers and container parts, the combination of a pair of rotatable members disposed one within the other in radial relation to their axis of rotation and having oppositely disposed faces engageable simultaneously with opposite surfaces of a marginal edge portion of a container part inserted between said faces, means for depositing on said faces a quantity of liquid coating material for transfer to said container part, and means for rotating said members to effect the transfer of the coating material to the container part from the faces on which it is carried.

2. In a device for applying liquid coating material to marginal edge portions of containers and container parts, the combination of a pair of rotatable members disposed one within the other and having oppositely disposed applying faces engageable simultaneously with opposite surfaces of a marginal edge portion of a container part inserted between said applying faces, one of said applying faces being disposed at an angle to the axis of rotation of said members, the rotation of said members being about a fixed axis disposed at an angle to the vertical so that container parts of different dimensions may be engaged by the faces of said members, means for depositing on at least one of said faces a quantity of liquid coating material for transfer to said container part, and means for rotating said members to effect the

transfer of the coating material to the container part from the face on which it is carried.

3. In a device for applying liquid coating material to marginal edge portions of containers and container parts, the combination of a pair of rotatable members disposed one within the other in relatively eccentric positions and having oppositely disposed faces engageable simultaneously with opposing surfaces of a marginal edge portion of a container part inserted between said faces, means for depositing on at least one of said faces a quantity of liquid coating material for transfer to said container part, and means for rotating said members to effect the transfer of the coating material to the container part from the face on which it is carried.

4. In a device for applying liquid coating material to marginal edge portions of containers and container parts, the combination of a pair of rotatable members, one of said members being rotatable on a fixed axis and the other rotatable member having a floating movement laterally of said axis to provide relative lateral movement between said members, said members being disposed one within the other in radial relation to their axis of rotation and having oppositely disposed faces engageable simultaneously with opposite surfaces of a marginal edge portion of a container part inserted between said faces, means for depositing on at least one of said faces a quantity of liquid coating material for transfer to said container part, and means for rotating said members to effect the transfer of the coating material to the container part from the face on which it is carried.

5. In a device for applying liquid coating material to marginal edge portions of containers and container parts, the combination of a pair of rotatable members disposed one within the other in radial relation to their axis of rotation and having oppositely disposed faces engageable simultaneously with opposite surfaces of a marginal edge portion of a container part inserted between said faces, one of said members having a floating mounting, pressure means for yieldingly holding the member having the floating mounting in operative position relative to the other of said member, means for depositing on at least one of said faces a quantity of liquid coating material for transfer to said container part, and means for rotating said members to effect the transfer of the coating material to the container part from the face on which it is carried.

6. In a device for applying liquid coating material to marginal edge portions of containers and container parts, the combination of a rotatable disc, a rotatable ring surrounding said disc, said disc and said ring having oppositely disposed faces engageable simultaneously with opposing surfaces of a marginal edge portion of a container part inserted between said faces, means for depositing on at least one of said faces a quantity of liquid coating material for transfer to said container part, and means for rotating said members in unison to effect the transfer of the coating material to the container part from the face on which it is carried.

7. In a device for applying liquid coating material to marginal edge portions of containers and container parts, the combination of a rotatable applying disc, a rotatable applying pressure ring surrounding said disc, said disc and said ring having oppositely disposed faces engageable simultaneously with opposing surfaces of a marginal edge portion of a container part inserted

between said faces, means for depositing on said faces a quantity of liquid coating material for transfer to said container part, and means for rotating said members in unison to effect the transfer of the coating material to the container part from the face on which it is carried.

8. In a device for applying liquid coating material to marginal edge portions of containers and container parts, the combination of a rotatable applying disc having two adjacent angularly disposed applying faces one of which is engageable with the edge of a part to be coated and the other engageable with a marginal portion adjacent said edge, a rotatable applying pressure ring surrounding said applying disc and having an applying face engageable with a marginal portion of said container part on an opposite side thereof and disposed adjacent the edge of said container part, means for rotating said disc and said ring in unison, and means for depositing on the applying faces of said disc and said ring a quantity of liquid coating material for transfer to the edge and marginal portions of a container part interposed between said disc and said ring so that these portions of the container part will be fully covered with a film of the coating material.

9. In a device for applying liquid coating material to marginal edge portions of containers and container parts, the combination of a rotatable applying disc having means for rotating the same, a rotatable applying pressure ring surrounding said applying disc in an eccentric position relative to said disc, said disc and said ring having oppositely disposed faces engageable with opposing surfaces of a marginal portion of a container part inserted between said faces, a driving gear on said disc, an internal gear on said ring in mesh with said driving gear for rotating said ring in unison with said disc, and means for depositing on the faces of said disc and said ring a quantity of liquid coating material for transfer to the marginal portion of a container part interposed between said disc and said ring so that these portions of the container part will be fully covered with a film of the coating material.

10. In a device for applying liquid coating material to marginal edge portions of containers and container parts, the combination of a rotatable applying member having two adjacently disposed applying faces one of which is engageable with the edge of a container part to be coated and the other of which is engageable with a marginal edge portion thereof adjacent the edge of the part to be coated, means for depositing on said applying faces a quantity of liquid coating material for transfer to the edge and marginal portions of said container part so that these portions will be fully covered with a film of coating material, and an annular pressure member rotatably surrounding said applying member in eccentric relation to the axis of the latter, said pressure member engaging said container part for pressing the marginal edge portion of the part

against the faces of said applying member to receive the film of coating material therefrom.

11. In a device for applying liquid coating material, to marginal edge portions of containers and container parts, the combination of an applying member having two adjacently disposed applying faces one of which is engageable with the edge of a part to be coated and the other of which is engageable with an inner marginal portion adjacent said edge of the part to be coated, both of said applying faces being disposed at an angle to the axis of rotation of said member, means for depositing on said applying faces a quantity of liquid coating material for transfer to the edge and marginal portions of said container part so that these portions will be fully covered with a film of coating material, an annular pressure member rotatably surrounding said applying member in eccentric relation to the axis of the latter, said pressure member engaging an outer marginal edge portion of said container part for pressing the marginal edge portion of the container part against the faces of said applying member to receive the film of coating material therefrom, and means for depositing on said pressure member a quantity of liquid coating material for transfer to the outer marginal edge portion of the container part simultaneously with the application of the coating material to the edge portion and the inner marginal portion.

12. In a device for applying liquid coating material to marginal edge portions of containers and container parts, the combination of an applying member having two adjacently disposed applying faces one of which is engageable with the edge of a part to be coated and the other of which is engageable with a marginal portion adjacent said edge of the part to be coated, both of said applying faces being disposed at an angle to the axis of rotation of said member, means for depositing on said applying faces a quantity of liquid coating material for transfer to the edge and marginal portions of said container part so that these portions will be fully covered with a film of coating material, an annular pressure member rotatably surrounding said applying member in eccentric relation to the axis of the latter, said pressure member engaging said container part for pressing the marginal edge portion of the container part against the faces of said applying element to receive the film of coating material therefrom, and means for yieldably holding said pressure member in operating position.
